UNITED STATES PATENT OFFICE.

HOWARD A. THOMPSON, OF WILKINSBURG, PENNSYLVANIA, ASSIGNOR TO UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 17, 1925. Serial No. 63,029.

My invention relates to railway traffic controlling apparatus, and particularly to apparatus of the type comprising governing means located on a train and controlled by energy received from the trackway. More particularly my invention relates to the trackway portion of such apparatus.

I will describe one form of trackway apparatus embodying my invention, and will then point out the novel features thereof in claims.

The accompanying drawing is a diagrammatic view illustrating one form of railway traffic controlling apparatus embodying my invention.

Referring to this drawing, the reference characters 1 and 1^a designate the track rails of a stretch of railway track over which traffic normally moves in the direction indicated by the arrow. These rails are divided, by means of insulated joints 2, into a plurality of successive track sections A—B, B—C, etc.

A track relay R² is connected across the rails adjacent the entrance end of section B—C and a similar relay R³ is connected across the rails adjacent the entrance end of the section to the right of point C. A similar track relay R¹ is connected across the rails adjacent the exit end of section A—B. Track circuit current is supplied to the rails of each section from a suitable source of direct current such as a track battery here designated by the reference character E with an exponent corresponding to the location. It should be noted that the track battery for section A—B is located at the entrance end of the section whereas the track battery for section B—C is located adjacent the exit end of the section.

Means are also provided for supplying alternating train controlling current to the rails of each track section. As here shown the immediate source of this train controlling current for each section is a main transformer designated by the reference character T with an exponent corresponding to the location. The primary 4 of each such main transformer is constantly supplied with alternating current from a suitable source, such as an alternator M, over line wires 3 and 3^a. Located adjacent the exit end of each track section is an auxiliary conductor, extending parallel to rail 1^a and designated

by the reference character F with a suitable distinguishing exponent. The purpose of these auxiliary conductors will be explained hereinafter.

Referring particularly to section A—B the reference character D^B designates a transformer, the primary 6 of which is connected with the secondary 5 of transformer T^B, through a back contact 10 of relay R¹ and the auxiliary conductor F^B. The secondary 7 of transformer D^B is connected across the rails adjacent the exit end of section A—B, through a front contact 11 of relay R² and the usual resistance 12. It follows that when relay R¹ is de-energized, as by the presence of a train in section A—B, the circuit for primary 6 of transformer D^B is closed, and magnetizing current is supplied to this transformer through the auxiliary conductor F^B from transformer T^B. If relay R² is energized while current is being supplied to the primary 6 of transformer D^B, train controlling current is supplied to the rails of section A—B from secondary 7 of transformed D^B. If, however, relay R² is de-energized, the supply of train controlling current to section A—B is interrupted, no matter what the condition of relay R¹.

Referring now to section B—C, the primary 6 of transformer D^C is connected constantly with secondary 5 of transformer T^C through auxiliary conductor F^C. The secondary 7 of transformer D^C is connected, through front contact 11 of relay R³, with the primary 8 of a transformer J. The secondary 9 of transformer J is connected across the rails of section B—C in series with the track battery E^C and the usual resistance 12 and reactor 13. The primary circuit for transformer D^C is closed at all times so that the magnetizing current for this transformer flows through the auxiliary conductor F^C, constantly. When relay R³ is energized current is supplied to the primary 8 of transformer J and as a result train controlling current is supplied to the rails of section B—C.

The trackway circuits thus far described are suitable for co-operation with train carried governing means of the type illustrated on the train V occupying the section to the left of point A. Carried on train V in advance of the front axle 16 is a pick-up device here shown as two magnetizable cores 14 and

14^a, located in inductive relation with the track rails 1 and 1^a, respectively. Core 14 is provided with a winding 15, and core 14^a is provided with a similar winding 15^a, the windings 15 and 15^a being so connected in series that the voltages induced therein by train controlling currents flowing in the two track rails in series are additive. Energy induced in windings 15 and 15^a is supplied to a relay K through an amplifier 16. It follows therefore that relay K is energized when the train occupies a stretch of track which is being supplied with train controlling current or when the winding 15^a is in inductive relation with an energized auxiliary conductor F. Relay K controls train carried governing means not shown in the drawing in such manner that the brakes are applied when relay K becomes de-energized unless the engineman acknowledges this change by taking some deliberate action to forestall the brake application. One form of train carried governing means which function in this manner is illustrated and described in United States Letters Patent No. 1,492,719, granted to R. A. McCann, on the 6th day of May, 1924, for railway traffic controlling apparatus.

In connection with the trackway apparatus it should be particularly noted that at times the current flowing through the auxiliary conductor is only the magnetizing current for the primary winding of the associated transformer D. At other times, however, that is, when the secondary circuit for the corresponding transformer D is closed, the current through the auxiliary conductor includes not only the magnetizing current but a load current. In my invention the apparatus is so proportioned that the voltage induced in the winding 15^a by current flowing through the auxiliary conductor under either of these conditions is sufficient to operate relay K.

As shown in the drawing, sections A—B and B—C and the section to the right of point C are unoccupied. Track relays R¹, R² and R³ are therefore all energized. Train controlling current is therefore supplied to the rails of section B—C from secondary 9 of transformer J. Alternating current is also supplied to auxiliary conductor F^c. The secondary circuit for transformer D^B is closed but the circuit for primary 6 of this transformer is open at back contact 10 of relay R¹. No train controlling current is supplied to section A—B, therefore, and no current is flowing in auxiliary conductor F^B.

When the train V enters section A—B, relay R¹ will become de-energized, thereby closing the primary circuit for transformer D^B and supplying alternating current to the auxiliary conductor F^B. At the same time train controlling current will be supplied to the rails of section A—B. Relay K will

therefore be energized and an automatic application of the brakes will be prevented. When the train enters section B—C the train controlling current supplied to the rails of this section will maintain relay K in its energized condition so that the train will be permitted to proceed without incurring an automatic application of the brakes.

I will now assume that section B—C is occupied by a train so that relay R² is de-energized. If, now, train V enters section A—B, relay R¹ will become de-energized as before, so that current will be supplied to the auxiliary conductor F^B, but relay R² being de-energized, no train controlling current will be supplied to the rails of section A—B. Relay K will therefore become de-energized and an automatic application of the brakes will result unless the engineman acknowledges. If the engineman does acknowledge the train can proceed until core 14^a passes over auxiliary conductor F^B, whereupon relay K will become energized. When the train carried core 14^a leaves the auxiliary conductor F^B relay K will again become de-energized and the engineman must again acknowledge to prevent an automatic application of the brakes.

Similarly if the section to the right of point C is occupied by a train, relay R³ will be de-energized and the train V entering section B—C will incur an automatic application of the brakes because of the de-energization of relay K unless the engineman acknowledges. When the train reaches auxiliary conductor F^c the magnetizing current for primary 6 of transformer D^c, which is flowing in this conductor, will again energize relay K. When the train carried pick-up device has moved away from the conductor F^c relay K will again become de-energized and the engineman must again acknowledge to prevent an automatic brake application.

I will assume that the stretch of track shown in the drawing is unoccupied and that a break occurs in the circuit including the auxiliary conductor F^B. When the train V enters section A—B the relay R¹ will become de-energized as before, but the primary circuit for transformer D^B is now interrupted and therefore no train controlling current can be supplied to the rails of sections A—B. The train will therefore incur an automatic brake application unless the engineman acknowledges. Similarly, if a break occurs in the circuit including auxiliary conductor F^c, the primary circuit for transformer D^c will be interrupted and the supply of train controlling current to section B—C will be discontinued.

It follows therefore that with my invention any break or fault in the circuit including one of the auxiliary conductors will result in preventing the supply of train con-

trolling current to the associated track section. A train entering such associated section will therefore receive a brake application unless the engineman acknowledges. 6 It follows that with apparatus embodying my invention the integrity of the circuits for the auxiliary conductors is completely checked, each portion of such circuits having to be intact in order that train controlling current may be supplied to the rails of the associated section.

10 Although I have herein shown and described only one form of railway traffic controlling apparatus embodying my invention, 15 it is understood that various changes and modifications may be made therein within the scope of the appended claims without departing from the spirit and scope of my invention.

20 Having thus described my invention, what I claim is:

1. In combination with a stretch of railway track and a transformer for at times supplying train controlling current to said 25 stretch, an auxiliary conductor located in the trackway and connected in series with the primary of said transformer, and train carried governing means responsive to the train controlling current in said stretch and also 30 responsive to the transformer magnetizing current flowing in said conductor.

2. In combination, a stretch of railway track, a source of alternating current, an auxiliary conductor located in the trackway, 35 a transformer having its primary connected in series with said auxiliary conductor and with said source, means for at times supplying train controlling current from the secondary of said transformer to the rails of the stretch, and train carried governing means responsive to alternating current flowing in the track rails and also to the magnetizing current for said transformer flowing in said conductor.

40 3. In combination, a stretch of railway

track, a relay responsive to traffic conditions in said stretch, an auxiliary conductor located in the trackway, a source of alternating current, a transformer; a circuit for the primary of said transformer including 50 said auxiliary conductor, said source, and a contact of said relay; means for supplying train controlling current from the secondary of said transformer to the rails of said stretch, and governing means on a train 55 controlled by energy received from the trackway.

4. In combination a stretch of railway track, a relay responsive to traffic conditions in said stretch, an auxiliary conductor located in the trackway, a source of alternating current, a transformer; a circuit for the primary of said transformer including 60 said auxiliary conductor, said source, and a contact of said relay; means for at times connecting the secondary of said transformer with the rails of said stretch, and governing means at times controlled by alternating current in the rails of said stretch, and at 65 times controlled by current in said conductor.

5. In combination with a stretch of railway track and train carried governing means responsive to alternating current flowing in the trackway, an auxiliary conductor 75 located in the trackway, a source of alternating current, a first transformer having its primary connected in series with said source and said auxiliary conductor, a relay responsive to traffic conditions in advance of 80 said stretch, a second transformer, a circuit for the primary of said second transformer including the secondary of said first transformer and a contact of said relay, and means for supplying alternating current 85 from the secondary of said second transformer to the rails of said stretch.

In testimony whereof I affix my signature.

HOWARD A. THOMPSON.

DISCLAIMER

1,610,394.—*Howard A. Thompson*, Wilkinsburg, Pa. RAILWAY-TRAFFIC-CONTROLLING APPARATUS. Patent dated December 14, 1926. Disclaimer filed June 22, 1933, by the assignee, *The Union Switch & Signal Company*.

Hereby enters the following disclaimer, to wit:
